DRAPERY PLEAT CLAMP AND ADJUSTABLE HOOK

Frank J. Roeckel, Indianapolis, Ind.

Application June 20, 1952, Serial No. 294,759

5 Claims. (Cl. 24—84)

1

This invention relates to a drapery pleat forming and retaining device including an adjustable hook for support purposes.

As is well known, most drapery pleats are formed by stitching. Once the desired type of pleat has been thus formed it is, of course, difficult from a practical point of view to vary it to a different type. Furthermore, a problem is presented in connection with the laundering or dry cleaning of the conventional drapery since the stitching is frequently ripped or torn, and since satisfactory cleaning is always difficult to accomplish. It is, therefore, the primary object of this invention to provide a device which makes possible the forming without any stitching of any one of a variety of pleat types. When it is desired to change the type, it can be accomplished readily with a maximum of ease. Furthermore, when the drapery is to be laundered or dry cleaned, the device can be removed thereby removing the pleats and making possible an effective overall cleaning of the drapery.

It is a further object of the present invention to provide a device of the above character which is of simple construction, inexpensive in price and easy to use.

It is a still further object of the present invention to provide a combined latching member and hook which serves a dual purpose in that it locks the pleat clamp in place while at the same time supports the drapery from the rod. Since the combined latching member and hook is removable and not permanently affixed to the structure nor to the drapery, one less problem is encountered when the draperies are dry cleaned or laundered.

It is a still further object of the present invention to provide a drapery hook which is vertically adjustable in such manner that the heading of the drapery may be varied within desired limits.

The full nature of the invention will be understood from the accompanying drawings and the following description and claims:

Fig. 1 is a perspective view of the invention in assembled position but without any drapery being shown.

Fig. 2 is a perspective view of a backing plate.

Fig. 3 is a perspective view of the clamp with the backing plate and hook removed.

Fig. 4 is a transverse section view on the line 4—4 of Fig. 1 in the direction of the arrows.

Fig. 5 is a side elevation view of the supporting and locking hook.

In the drawings there is shown a front plate 10 having an aperture 11, a struck-out resilient clasp 12 and a slot or notch 13. Engageable over

2

one end of the front plate are the resilient, substantially J-shaped clamping elements 14 which are preferably but not necessarily of serpentine formation. With this construction it is possible to loosely wrap a portion of the drapery material around the plate and then weave it in between the clamping elements and the plate. The clamping elements will retain the material in the desired formation. For example, it is possible to loosely wrap the material around the plate, leaving a loop to form a so-called bullet type of pleat. Or if desired, the material may be tightly pulled about one face of the plate and retained in that position, thereby forming a so-called flat pleat. Furthermore, if desired, a pinch type pleat may be formed by first providing a loop and then tacking the material in such manner that the pleat is thereby formed.

Once the desired type of pleat is fashioned then the backing plate 15 may be applied to the front plate 10 in face to face relation in the manner shown in Fig. 1. This backing plate has a struck-out and resilient clasp or clip portion 16 which is formed at such position in the plate as to enable it to extend through the aperture formed in the front plate. An aperture 17 is formed in the backing plate at a point in alignment and register with the clasp 12 of the front plate, and is of such a size as to permit said clasp to extend therethrough. It will be observed that both the front and the backing plate have an aperture and a struck-out clasp. As a consequence of this construction, once the backing plate is applied in face to face relation to the front plate, the clasp 16 will extend through the aperture 11 whereas the clasp 12 will extend through the aperture 17, thereby providing a projecting clasp on both sides of the assembled structure.

It will also be observed that the area adjacent the side edges of the backing plate is cupped or dished out as shown at 18. This is done to provide for the reception of the clamping elements 14 and at the same time permit the area of the backing plate lying between the dished out portions to abut that portion of the front plate lying between the clamping elements. As a consequence the clasps of both plates can be made of shorter length and will readily extend through and beyond the apertures of the other. But more important, the concavities or dished out portions serve as means to hold the drapery clamping elements in place and prevent any lateral movement.

Once the backing plate has been applied in interfitting or face to face relation to the front

3

plate, the latching means shown generally at 19 and including a hanging hook is placed in position as shown in Fig. 1 in order to retain the assembled plates in face to face relation. The latching member comprises an elongated leg 20 and a shorter leg 20a terminating in the hook 21. The shorter leg has several offset portions 22, 23 and 24 for a purpose hereinafter described.

In assembling the device after the drapery material has been woven between the clamping elements 14 and the front plate, the user can first hold the plates in position with the forefinger and thumb of one hand while the other hand is used to extend the elongated leg of the latching member up through the clasp 16. At 15 the same time the shorter leg of the latching member will be disposed on the opposite side of the assembled plates with one of the offset portions disposed under clasp 12. In Fig. 1 of the drawings the latching member is shown with the 20 offset portion 24 engaged by one of the clasps. As is apparent, the latching member is incapable of more than very limited vertical movement. Should it be desirable to lengthen the heading it is necessary only that one of the other offset portions, namely 22 or 23, be disposed adjacent to and engaged by the clasp 12. In short, the length of the heading may selectively be varied as the occasion warrants. The notch 13 serves, in combination with the clasps, to prevent transverse or lateral movement of the hook. Furthermore, the provision of the notch or slot makes possible the use of a shorter latching member, thereby requiring lesser material to be used in forming it.

When it is desired to change the type of drapery pleat it is obvious that the invention may be disassembled with ease whereupon the change in type of pleat can be readily accomplished.

With this construction the invention is hidden from view as is apparent by reference to Fig. 4.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

The invention claimed is:

1. A drapery pleat clamp and hook structure comprising a plate having an aperture and an outwardly projecting clasp, a pair of drapery clamping elements detachably carried by said plate, a second plate associated with said first plate and having an aperture receiving therethrough the clasp of said first plate and an outwardly projecting clasp in register with and extending through the aperture of said first plate, and latching means terminating in a hook and retaining said plates in interfitting relation, said means including legs engageable by said clasps on opposite sides of the associated plates.

2. A drapery pleat clamp and hook structure comprising a pair of face to face plates each having at least one aperture and one projecting clasp, the clasp of each plate being in register with and extending through and beyond the aperture of the other, a pair of drapery clamping elements disposed between said plates and detach-

ably carried by one of said plates, the other of said plates having means preventing lateral movement of said elements, and latching means terminating in a hook and retaining said plates in face to face relation, said latching means including legs extending through said respective clasps on opposite sides of said plates.

3. A drapery pleat clamp and hook structure comprising a pair of face to face plates each having at least one aperture and one projecting clasp, the clasp of each plate being in register with and extending through and beyond the aperture of the other, a pair of drapery clamping elements disposed between said plates and detachably carried by one of said plates, the other of said plates having concave portions formed therein for receiving said elements and preventing their lateral movement, and substantially J-shaped latching means terminating in a hook for retaining said plates in face to face relation, said means having legs engageable by said respective clasps on opposite sides of said plates.

4. A drapery pleat clamp and adjustable hook structure comprising a pair of face to face plates each having at least one aperture and one projecting clasp, the clasp of each plate being in register with and extending through and beyond the aperture of the other, a pair of drapery clamping elements disposed between said plates and detachably carried by one of said plates, the other of said plates having means preventing lateral movement of said elements, said plates having vertically disposed and aligned notches formed in one end thereof, and latching means extending 35 through said notches and terminating in a hook and retaining said plates in face to face relation, said latching means having legs engageable by said respective clasps on opposite sides of said plates, one of the legs of said latching means having a plurality of offset portions each being selectively engageable by one of said clasps.

5. A drapery pleat clamp and adjustable hook structure comprising a pair of face to face plates each having at least one aperture and one projecting clasp, the clasp of each plate being in register with and extending through and beyond the aperture of the other, a pair of drapery clamping elements disposed between said plates and detachably carried by one of said plates, the other of said plates having concave portions formed therein for receiving said elements and preventing their lateral movement, said plates having vertically disposed and aligned notches formed in one end thereof, and substantially J-shaped latching means extending through said notches and terminating in a hook and retaining said plates in face to face relation, said member having legs engageable by said respective clasps on opposite sides of said plates, one of the legs of said latching means having a plurality of offset portions each being selectively engageable by one of said clasps.
